UNITED STATES PATENT OFFICE

2,439,167

DECOY

Marshal E. Jackson, Kalamazoo, Mich.

Application March 4, 1946, Serial No. 651,811

8 Claims. (Cl. 43—3)

1

This invention relates to improvements in decoys.

The main objects of this invention are:

First, to provide a decoy which may be compactly collapsed and at the same time one which is effectively held in erected position and is capable of withstanding quite severe shocks and strains when erected.

Second, to provide a decoy which has an effective simulation of the object it is intended to represent, and at the same time may be very economically produced.

Third, to provide a decoy which may be collapsed for storage or transportation and quickly erected as occasion may require.

Objects relating to details and economies of the invention will appear from the description to follow. The invention is defined in the claims.

A structure which embodies the features of the invention is illustrated in the accompanying drawing, in which:

Fig. 1 is a side elevation of a decoy representing a goose, embodying my invention fully erected.

Fig. 2 is an enlarged fragmentary view partially in longitudinal section with the supporting post or shaft in collapsed position, parts being shown conventionally.

Fig. 3 is a front elevation with the supporting rod removed.

Fig. 4 is a dis-assembled view of the parts collapsed.

Fig. 5 is an enlarged fragmentary view illustrating certain details of the support.

In the accompanying drawing 1 represents the ground. The decoy of my invention comprises a body wall element 2 formed of flexible fabric, canvas or duck or the like being a desirable material. This body wall element is shaped to simulate the desired object, in the embodiment illustrated being designed to simulate a goose. The body wall element is of circular section and is provided with a plurality of internal annular supporting ribs 3, these ribs being disposed transversely in longitudinal spaced relation within the wall element and secured thereto by means of the strips 4 stitched to the wall element to embrace the ribs. The ribs are independent of each other, except as they are connected through the wall element.

The ribs are of diameters corresponding to the internal cross sectional diameter of the wall element at the zones in which the ribs are disposed. This permits the longitudinal collapsing of the body member with a series of shallow folds be-

2

tween the ribs, this collapsed position being indicated at 5 in Fig. 4.

The wall element has an upwardly extended neck portion 6 in which the disk 7 is secured as by means of the tacks or brads 8. The conical socket 9 is secured within the rear end of the wall element to face forwardly therein, the socket being of metal and having holes 10 around its edge receiving the stitches 11.

10 The head 12 is provided with a stem or shank 13 detachably engageable with the hole 14 in the disk 7. A curved plate 15 is secured within the body at the front end thereof, the plate being curved to conform with the body at the breast portion thereof. The plate is secured by the stitches 16 through holes 17 provided therefor at the edges of the plate. The plate has a hole 18 adapted to receive the arm 19 of the supporting rod 20. This supporting rod is desirably curved 15 to correspond to the front portion of the body wall element and to engage between forwardly projecting lugs 21 on the plate 15 when the arm 19 is inserted through the hole 18 and engaged with the socket 9.

25 The hole 18 is a key-hole shape, that is, it is provided with a slot 22, this slot being adapted to receive the stud 23 on the arm 19 when the stud is placed in alignment with the slot 22. A quarter-rotation of the support on its arm brings 30 the support in position to engage the lugs 21 and swings the stud 23 in position to engage the inner side of the plate 15. This locks the parts with the body in fully extended position.

The supporting rod 20 may be sprung sufficiently 35 to permit its engagement between the lugs 21.

The shaft or post portion 24 of the supporting rod is pivoted to the shank portion 25 of the supporting rod at 26. The sleeve 27 is slidable on this shank to be moved downwardly over the joint 40 of the post or shaft to the shank as shown in Fig. 1, thereby holding the shaft in erected position. The pin 28 serves as a stop for the sleeve.

With the sleeve adjusted to the position shown 45 in Fig. 2, the shaft may be collapsed in substantially parallel relation to the body. In practice the wall element is desirably made water proof and painted or otherwise decorated as may be desired. The head member may also be suitably painted, but I have not attempted to illustrate this or the ornamentation of the body.

I have illustrated and described one practical embodiment or adaptation of my invention. I have not attempted to illustrate or describe other adaptations which I contemplate, as it is believed 55 that this disclosure will enable those skilled in

the art to embody or adapt my invention as may be desired.

Having thus described my invention, what I claim as new and desire to secure by Letters Patent is:

1. A decoy comprising a flexible fabric body wall element conformed longitudinally and transversely to simulate an object and comprising a rearwardly tapered rear portion and an upturned neck portion, a plurality of internal annular wall element ribs disposed transversely in longitudinally spaced relation within the wall element and secured to the inner side thereof to permit longitudinal collapsing of the wall element, the ribs having diameters corresponding to internal cross sectional diameters of the wall element at the zones in which the ribs are disposed, a conical socket secured at the rear end of said wall element to face forwardly therein, a disk secured within the upturned neck portion of the wall element and having an opening therein, a head member having a shank removably engageable with said opening in said disk, a plate secured within the wall element at the front end thereof and having an opening therein, there being a slot at one side of the opening, said plate having a pair of outwardly projecting lugs below said opening, and a supporting rod having an arm disposed through said opening in said plate and engaged in said socket whereby the wall element is supported in erected position, said arm having a stud adapted to be passed through said slot when aligned therewith and engaging the inner side of the plate when said support is positioned to engage said lugs on said plate, said support having a shaft portion pivoted to the lower end thereof to permit collapsing parallel with the erected body, and a sleeve slideable on said support for holding said shaft in erected position.

2. A decoy comprising a flexible fabric body wall element conformed longitudinally and transversely to simulate an object and comprising a rearwardly tapered rear portion and an upturned neck portion, a plurality of internal annular wall element ribs disposed transversely in longitudinally spaced relation within the wall element and secured to the inner side thereof to permit longitudinal collapsing of the wall element, the ribs having diameters corresponding to internal cross sectional diameters of the wall element at the zones in which the ribs are disposed, a conical socket secured at the rear end of the said wall element to face forwardly therein, a disk secured within the upturned neck portion of the wall element and having an opening therein, a head member having a shank removably engageable with said opening in said disk, a plate secured within the wall element at the front end thereof and having an opening therein, a supporting rod having an arm disposed through said opening in said plate and engaged in said socket whereby the wall element is supported in erected position.

3. A decoy comprising a flexible fabric body wall element conformed longitudinally and transversely to simulate an object and comprising a rearwardly tapered rear portion and an upturned neck portion, a plurality of internal annular wall element ribs disposed transversely in longitudinally spaced relation within the wall element and secured to the inner side thereof to permit longitudinal collapsing of the wall element, the ribs having diameters corresponding to internal cross sectional diameters of the wall element at the zones

in which the ribs are disposed, an inwardly facing socket at the rear end of said wall element, a disk secured within the upturned neck portion of the wall element and having an opening therein, a head member having a shank removably engageable with said opening in said disk, a plate at the front end of the wall element, having an opening therein, there being a slot at one side of the opening, said plate having a pair of outwardly projecting lugs below said opening, and a supporting rod having an arm disposed through said opening in said plate and engaged in said socket whereby the wall element is supported in erected position, said arm having a stud retainingly engaging the plate when the arm is rotated to position said support in upright position, said support having a shaft portion pivoted to the lower end thereof to permit collapsing parallel with the erected body, and means for holding said shaft in erected position.

4. A decoy comprising a flexible fabric body wall element conformed longitudinally and transversely to simulate an object and comprising a rearwardly tapered rear portion and an upturned neck portion, a plurality of internal annular wall element ribs disposed transversely in longitudinally spaced relation within the wall element and secured to the inner side thereof to permit longitudinal collapsing of the wall element, the ribs having diameters corresponding to internal cross sectional diameters of the wall element at the zones in which the ribs are disposed, an inwardly facing socket at the rear end of said wall element, a disk secured within the upturned neck portion of the wall element and having an opening therein, a head member having a shank removably engageable with said opening in said disk, a plate at the front end of the wall element, having an opening therein, there being a slot at one side of the opening, said plate having a pair of outwardly projecting lugs below said opening, and a supporting rod having an arm disposed through said opening in said plate and engaged in said socket whereby the wall element is supported in erected position, said arm having a stud retainingly engaging the plate when the arm is rotated to position said support in upright position.

5. A decoy comprising a flexible fabric body wall element conformed longitudinally and transversely to simulate an object and comprising a rearwardly tapered rear portion and an upturned neck portion, a plurality of internal annular wall element ribs disposed transversely in longitudinally spaced relation within the wall element and secured to the inner side thereof to permit longitudinal collapsing of the wall element, the ribs having diameters corresponding to internal cross sectional diameters of the wall element at the zones in which the ribs are disposed, an inwardly facing socket at the rear end of said wall element, a disk secured within the upturned neck portion of the wall element and having an opening therein, a head member having a shank removably engageable with said opening in said disk, a plate at the front end of the wall element, having an opening therein, there being a slot at one side of the opening, said plate having a pair of outwardly projecting lugs below said opening, and a supporting rod having an arm disposed through said opening in said plate and engaged in said socket whereby the wall element is supported in erected position.

6. A decoy comprising a flexible fabric body wall element, a plurality of internal annular wall

element ribs disposed transversely in longitudinally spaced relation within the wall element and secured to the inner side thereof to permit longitudinal collapsing of the wall element, a socket at the rear end of said wall element, a plate secured at the front end of the wall element and having a keyhole opening therein, said plate having a pair of outwardly projecting lugs below said opening, and a supporting rod conformed to the wall element at the front thereof and having an arm disposed through said opening in said plate and engaged in said socket whereby the wall element is supported in erected position, said arm having a stud adapted to be passed through said key-hole opening when presented in alignment with the slot portion thereof and engaged with the plate when said rod is positioned to engage said lugs on said plate.

7. A decoy comprising a flexible fabric body wall element, a plurality of internal annular wall element ribs disposed transversely in longitudinally spaced relation within the wall element and secured to the inner side thereof to permit longitudinal collapsing of the wall element, a socket at the rear end of said wall element, a plate secured at the front end of the wall element and having an opening therein, and a supporting rod

10

20

having an arm disposed through said opening in said plate and engaged in said socket whereby the wall element is supported in erected position.

8. A decoy comprising a flexible fabric body wall element, a plurality of internal annular wall element ribs disposed transversely in longitudinally spaced relation within the wall element and secured to the inner side thereof to permit longitudinal collapsing of the wall element, said ribs being independent except as connected through their connection to said wall element, a socket at the rear end of said wall element, a plate secured at the front end of the wall element and having an opening therein, and a support having an arm disposed through said opening in said plate and engaged in said socket whereby the wall element is supported in erected position.
